HYDROCARBON CONVERSION PROCESS

Davis Read, Jr., Riverside, Ill., assignor to Universal Oil Products Company, Chicago, Ill., a corporation of Delaware

Original application April 29, 1940, Serial No. 332,136. Divided and this application September 27, 1943, Serial No. 503,903

3 Claims. (Cl. 196—49)

1

This application is a division of Serial No. 332,136 filed April 29, 1940, which has matured into Patent No. 2,336,126, dated December 7, 1943.

This invention relates to a process for converting relatively wide boiling range hydrocarbon oils into high yields of high antiknock gasoline and more specifically it is concerned with an improvement in the art of cracking hydrocarbon oil wherein a relatively heavy hydrocarbon oil is non-catalytically cracked and relatively light hydrocarbon oil catalytically cracked in the presence of a catalyst suspended therein. The improvement principally involves quenching the stream of hydrocarbon oils containing the suspended catalyst as it leaves the reaction zone to arrest the cracking reaction, whereby to reduce to a minimum the formation of carbonaceous and residual material.

I have found that in the catalytic cracking of hydrocarbon oil in the presence of a catalyst suspended therein, the reaction is usually accomplished at high temperatures and if the catalyst is allowed to remain in contact with the oil after the desired reaction is accomplished, unusually high amounts of carbonaceous materials are formed which are deposited with the catalyst in the separating zone.

In view of the above, my invention provides for quenching the stream of hydrocarbon oil containing the suspended catalyst as it leaves the reaction zone to reduce the temperature thereof to a temperature below that at which cracking is effected, after which the mixture is supplied to a vaporizing and separating chamber wherein vaporous conversion products are substantially separated from the heavier hydrocarbons and catalyst.

In one specific embodiment, the invention comprises subjecting a relatively heavy hydrocarbon oil to pyrolytic cracking in a heating coil and communicating reaction chamber, separating non-vaporous liquid residue from the pyrolytically formed vaporous conversion products, simultaneously therewith commingling a slurry of cracking catalyst with a relatively light hydrocarbon oil and passing the mixture through a reaction zone wherein it is heated to a catalytic cracking temperature, quenching the heated stream of hydrocarbon oil and catalyst leaving the reaction zone to arrest the cracking reaction, supplying the quenched stream of oil and catalyst to a vaporizing and separating chamber wherein said catalyst is reduced to a substantially dry powder containing a high proportion of carbonaceous materials by separating therefrom the

2

vaporous products, commingling said vaporous products with said pyrolytic vaporous conversion products and fractionating the mixture together with the charging oil to separate fractionated vapors boiling in the range of gasoline from the higher boiling conversion products and charging oil, recovering said fractionated vapors, withdrawing said higher boiling conversion products and charging oil as light and heavy reflux condensates, supplying said heavy reflux condensate to the pyrolytic conversion treatment as said relatively heavy oil and supplying at least a portion of said light reflux condensate to the catalytic conversion step as said relatively light hydrocarbon oil.

The accompanying diagrammatic drawing illustrates in conventional side elevation one specific form of the apparatus which may be employed to accomplish the objects of the invention.

Referring now to the drawing, heavy reflux condensate formed in the manner to be described later is supplied to heating coil 1. The heavy reflux condensate in passing through heating coil 1 is raised to the desired conversion temperature which may range, for example, from 850 to 1000° F., or more, by means of heat supplied from furnace 2. The heavy reflux condensate leaving heating coil 1 at an outlet pressure ranging, for example, from 100 to 500 pounds or more per square inch is directed through line 3 and valve 4 into reaction chamber 5. Reaction chamber 5 is preferably maintained at substantially the same pressure or at a slightly lower pressure than that employed on the outlet of heating coil 1 and is preferably insulated to reduce radiation losses therefrom, although no insulation is shown in the drawing.

The heated reflux condensate in passing through reaction chamber 5 is subjected to prolonged pyrolytic conversion at the elevated temperature and the resulting conversion products are discharged therefrom through line 6 and valve 7 into vaporizing and separating chamber 8. Vaporizing and separating chamber 8 is preferably maintained at a reduced pressure relative to that employed in reaction chamber 5 ranging, for example, from substantially atmospheric to 400 pounds or more per square inch in order to obtain a separation between the vaporous and liquid conversion products and to effect substantial further vaporization of the liquid conversion products to form a non-vaporous liquid residue. Non-vaporous liquid residue separated in chamber 8 is removed therefrom by way of line 9 and

valve 10 and may be recovered as a product of the process or subjected to any desired further treatment. Vaporous conversion products, together with vapors evolved within chamber 8, are directed through line 11 and valve 12 into fractionator 13 for treatment in the manner to be described later.

Simultaneously with the pyrolytic conversion treatment of the heavy reflux condensate as above described, light reflux condensate to which powdered catalyst is added in the manner to be described later, is supplied to heating coil 14. The slurry of catalyst and oil in passing through heating coil 14 is raised to the desired conversion temperature ranging, for example, from 500 to 1200° F., heat being supplied by means of furnace 15. Preferably also, heat is supplied to the slurry of catalyst and oil in heating coil 14 at a rapid rate so as to minimize the amount of pyrolytic cracking effected and increase the amount of catalytic cracking. When desired, a reaction zone other than a heating coil may be employed, however, in view of the fact that control of the heating is more readily obtained in a heating coil than in other types of reaction vessels the method illustrated is the preferred method.

The heated mixture of oil and catalyst leaving heating coil 14 at a pressure ranging, for example, from substantially atmospheric to 1000 pounds or more per square inch is directed through line 16 and valve 17 and, in accordance with the objects of the invention, is commingled with a cooler stream of hydrocarbon oil introduced in the manner to be described later in order to quench the stream of hot oil to a temperature ranging, for example, from 400 to 800° F., and the resulting mixture of conversion products, cooling oil, and catalyst is supplied to vaporizing and separating chamber 18. Chamber 18 is preferably operated at a reduced pressure relative to that employed on the outlet of heating coil 14 ranging, for example, from substantially atmospheric to 400 pounds or more per square inch whereby to separate vaporous conversion products and catalyst.

Chamber 18 is operated as a catalyst separating chamber wherein the catalyst is reduced to a substantially dry powder containing a high proportion of carbonaceous materials formed by reducing the liquid residue to a substantially dry coke. It would be desirable to employ more than one chamber in order that one or more of the chambers may be cleaned while another or others are employed in the conversion treatment. In this type of operation, the catalyst is removed as a substantially dry powder containing a high proportion of carbonaceous material and may be supplied to a catalyst regenerating system not shown in the drawing to prepare the catalyst for reuse.

The vaporous conversion products separated in chamber 18 are removed therefrom by way of line 33 and directed through valve 34 into line 11, commingling therein with the vapors removed from chamber 8, which mixture is supplied to fractionator 13. Fractionator 13 and the condensing and receiving equipment in communication therewith are preferably operated at a superatmospheric pressure of the same order as that employed in chambers 8 and 18. Simultaneously with the introduction of the vaporous products to fractionator 13, charging oil which may comprise, for example, a relatively wide boiling range hydrocarbon oil such as crude oil or reduced crude oil or any desired fraction thereof,

is introduced through line 35 and valve 36 to pump 37, which discharges the charging oil through line 38 and valve 39 into fractionator 13.

The charging oil and vaporous products supplied to fractionator 13 are fractionated therein to separate fractionated vapors boiling substantially in the range of gasoline from the higher boiling conversion products and heavier portions of the charging oil, the latter being withdrawn as light and heavy reflux condensates. Fractionated vapors separated in fractionator 13 are directed through line 40 and valve 41 to cooling and condensation in condenser 42. Distillate, together with undissolved and uncondensed gases from condenser 42, is directed through line 43 and valve 44 into receiver 45 wherein the distillate and gases are collected and separated. Normally gaseous products collected and separated in receiver 45 are removed therefrom by way of line 46 and valve 47 and recovered as a product of the process or subjected to any desired further treatment. A portion of the distillate collected and separated in receiver 45 may be returned to the upper portion of fractionator 13 to serve as a refluxing and cooling medium while the residual portion thereof may be removed from receiver 45 by way of line 48 and valve 49 and recovered as a product of the process.

Heavy reflux condensate condensed and separated within fractionator 13 is removed therefrom by way of line 50 and is directed through valve 51 to pump 52, which discharges through line 53 and valve 54 into heating coil 1, the heavy reflux condensate being subjected to treatment as previously described.

Light reflux condensate separated in fractionator 13 is directed through line 55 and valve 56 to pump 57. Pump 57 discharges through line 58 and a portion is directed through line 59 and valve 62 into line 16 to serve as a quenching oil as previously described. Still another portion thereof may be removed from the system by way of line 63 and valve 64 for use in preparing the catalyst slurry in the manner to be described later. The residual portion of the light reflux condensate in line 58 is directed through valve 65 and is commingled with a slurry of cracking catalyst prepared in the same manner to be described later and the mixture supplied to heating coil 14 for treatment as previously described.

The catalyst slurry comprising, for example, a mixture of powdered cracking catalyst and light reflux condensate or any relatively light hydrocarbon oil of characteristics similar to those of the light reflux condensate is supplied to the system by way of line 66 and is directed through valve 67 to pump 68 which discharges through line 69 and valve 70 into line 58, commingling therein with the light reflux condensate as previously described.

Catalysts which have been found to be effective in the catalytic cracking of hydrocarbon oils may comprise, for example, powder or granules of silica or other siliceous and refractory materials composited with compounds selected from the group consisting of alumina, zirconia, vanadia, and thoria. In addition, the hydrosilicates of alumina, acid treated clays, or the like, have also been found to be effective in the cracking treatment of hydrocarbon vapors.

Although the catalysts above recited are generally considered to be the preferred catalysts, their use is not to be construed as a limiting feature, for various other catalysts well known to

those in the art may be employed within the broad scope of the invention.

I claim as my invention:

1. A process for the production of motor fuel which comprises subjecting a relatively heavy hydrocarbon oil to pyrolytic cracking in a heating coil and communicating reaction chamber, separating non-vaporous liquid residue from the pyrolytically formed vaporous conversion products, simultaneously therewith commingling a slurry of cracking catalyst with a relatively light hydrocarbon oil and passing the mixture through a reaction zone wherein it is heated to a catalytic cracking temperature, commingling a relatively cool oil with the heated stream of hydrocarbon oil and catalyst leaving the reaction zone to arrest the cracking reaction, supplying the quenched stream of oil and catalyst to a vaporizing and separating chamber wherein said catalyst is reduced to a substantially dry powder containing a high proportion of carbonaceous materials by substantially completely vaporizing the hydrocarbon introduced to said chamber and separating therefrom vaporous products substantially free of entrained catalyst, commingling the last-named vaporous products with said pyrolytic vaporous conversion products and fractionating the mixture together with the charging oil to separate fractionated vapors boiling in the range of gasoline from the higher boiling conversion products and charging oil, recovering said fractionated vapors, withdrawing said higher boiling conversion products and charging oil as light and heavy reflux condensates, supplying said heavy reflux condensate to the pyrolytic conversion treatment as said relatively heavy oil and supplying a portion of said light reflux condensate to the catalytic conversion step as said relatively light hydrocarbon oil, and utilizing another portion of said light reflux condensate as said relatively cool oil.

2. A process for the production of motor fuel, which comprises subjecting a relatively heavy oil to pyrolytic cracking, separating the resulting conversion products into pyrolytic vaporous conversion products and non-vaporous liquid residue, simultaneously therewith commingling a relatively light hydrocarbon oil with powdered cracking catalyst to form a slurry, supplying the resulting slurry to a reaction zone wherein it is

50

heated to a conversion temperature, quenching the stream of hot oil and catalyst leaving said reaction zone to arrest the cracking reaction by commingling therewith a colder stream of hydrocarbon oil, supplying the resulting mixture of cooling oil, catalyst, and catalytic conversion products to a vaporizing and separating chamber wherein said catalyst is reduced to a substantially dry powder containing a high proportion of carbonaceous materials by substantially completely distilling therefrom vaporous products substantially free of entrained catalyst, commingling said vaporous products with said pyrolytic vaporous conversion products and fractionating the mixture together with the charging oil to separate fractionated vapors boiling in the range of gasoline from the higher boiling conversion products and charging oil, recovering said fractionated vapors, withdrawing said higher boiling conversion products and charging oil as light and heavy reflux condensates, supplying said heavy reflux condensate to the pyrolytic conversion treatment as said relatively heavy oil, supplying a portion of said light reflux condensate to the catalytic conversion step as said relatively light hydrocarbon oil, and supplying another portion of the light reflux condensate to the aforesaid quenching step as said colder stream of oil.

3. A hydrocarbon oil conversion process which comprises fractionating the charging oil in contact with cracked vapors to form a relatively heavy fraction and a lighter fraction, thermally cracking the heavy fraction and separating resultant cracked vapors from residual products, commingling a cracking catalyst with a portion of said lighter fraction and subjecting the resultant mixture to catalytic cracking conditions while passing through a conversion zone, quenching the effluent of said conversion zone by commingling therewith another portion of said lighter fraction, separating the commingled materials into vapors and catalyst-containing residue, supplying thus separated vaporous products of the catalytic cracking and vaporous products of the thermal cracking to the aforesaid fractionating step for fractionation therein together with the charging oil, and finally condensing the fractionated vapors.
